UNITED STATES PATENT OFFICE.

EMMETT F. HICKMAN, OF NORFOLK, VIRGINIA, ASSIGNOR OF ONE-HALF TO ALBERT MUNDEN, OF NORFOLK, VIRGINIA.

LIFE-SAVING SUIT OR GARMENT.

1,117,571.

Specification of Letters Patent. Patented Nov. 17, 1914.

Application filed November 26, 1913. Serial No. 803,297.

To all whom it may concern:

Be it known that I, EMMETT F. HICKMAN, a citizen of the United States, residing at Norfolk, in the county of Norfolk and State of Virginia, have invented certain new and useful Improvements in Life-Saving Suits or Garments, of which the following is a specification.

My invention relates to life saving suits or garments.

The object of the invention is to provide means by which lives may be saved from drowning in shipwrecks or other disasters.

Further objects and advantages will be more fully described herein and specifically pointed out in the claims, recourse being had to the accompanying drawings forming a part of this specification in which:

Figure 1 is a front view of the device or 20 garment. Fig. 2 is a plan of the air inlet plate or register. Fig. 3 is a side elevation of the same. Fig. 4 is a front view upon an enlarged scale of the head or body portion of the suit or garment. Fig. 5 is a sectional plan of the head portion taken on the line 1—2 in Fig. 4. Fig. 6 is a plan of one of the inner tubes of the buoyant rings or tube casings. Fig. 7 is a fragmentary section of the garment showing an additional lining 25 forming air compartments therein, and Fig. 8 is an elevation of a rubber cap used as an auxiliary to insure a more perfect preventative against the entrance of water to the garment.

30 In the drawings like reference numerals indicate similar parts in all the several views:

1 is the body portion of the garment having the leg and feet members 2 as well as the arms 3 terminating in mitts or gloves as shown in Fig. 1. The body portion from the feet to the knees thereof is suitably lined with wool felt; the rest of the garment, except the head portion, is lined with wool 45 cloth. The feet portions are heavily lined with felt or other material for warmth and as an aid for keeping the body upright in the water. The garment is adapted for men, women and children and the outer material or fabric may be made of light duck, 50 rubber or other light impervious material.

4 is the head or upper portion of the garment and is heavily lined with wool felt, the head portion being open at the top, as 55 at 5, in Figs. 1 and 5. The head portion is

provided with celluloid, mica or glass windows or sights 6.

7 is an air inlet or register having a rotatorily operated closing plate 8 so that the air inlet gauze or perforations 9 may be closed to exclude water until the head of the wearer of the garment is above the surface at which time the air inlet may be uncovered to admit air within, as desired.

10 is a handle mounted on the movable 65 closing plate 8 for convenience in operating the same, also for the purpose of pumping air into the garment by pulling the handle in and out by hand in the manner of a bellows by which means air may be drawn 70 through the gauze or perforations 9 to the interior of the garment at will. The plate 8 is firmly held to the gauze or perforated plate 7 by means of the screw 11 and spring 12, Fig. 3.

13 are a series of rubber casings or rings around the waist portion of the garment and contain inner or inflation tubes 14, Figs. 1 and 6, the latter having their two ends closed and lapped, as shown in Fig. 6 at 15. 80

16 (Fig. 1) are inflating pipes communicating with the inner tubes 14 by which they are inflated either by means of a pump or other means. The pipes 16 are suitably fitted with unions, nipples and check or 85 non-return valves, as at 17, to prevent the escape of air from the tubes 14. The check valves, by means of the nipples and unions, may be taken out renewed or cleaned, as 90 may be desired.

18 are mouth pieces of the tubes 16 and 19 is a strap for holding the tubes to the outer fabric of the garment, as shown in Fig. 1.

20, Fig. 1, are dotted lines showing the 95 tubes 16 when it is desired to let them pass through the fabric of the garment and be combined by a suitable connection or mouth piece whereby the suit may be inflated from within the same by the wearer.

The outer rings or casings 13 have openings 21 for the insertion of the inner tubes and after they are placed therein the openings are tightly laced, as shown in Fig. 1.

When it is desired to use the garment, the 105 feet of the wearer are inserted into the portion 2 and the head portion 4 drawn up from a collapsed position, (shown by the dotted lines 22 in Fig. 1,) over the head of the wearer and tied so as to close the end or 110

open portion 5 in the manner of a bag or sack, by means of the tying ropes or draw straps 23. The straps 23 are held in position on the head portion by means of the box loops 24, as shown.

25 (Fig. 4) shows the knots when the head portion is gathered and tied when the garment is to be used.

In order to make a tight joint or closure, 10 a bundle of woolen threads or yarn, forming a compressible cushion or "squeezing" medium 26, is placed in the opening 5 of the head or top portion 4, Fig. 5, so that the water repelling wool may form a core thereby 15 and the stiff folds of the fabric may be closed thus preventing a leakage of water. The wool or yarn is suitably secured to the neck of the portion 4 by a strap 27 or other means.

20 In order to more fully provide against leakage, the cap 28 is provided having an elastic rim 29, the cap being adapted to fit over the tied portion of the head or upper member 4 of the garment.

25 Fig. 7 shows a modified garment having air cells or compartments 30 formed by an additional inner fabric 31 when it is desired to use such a modification.

The tubes 13 are of such size as to be sufficient 30 to support any weight with safety and vary according to the size or weight of the person for which the garment is intended.

The device, as shown, may be quickly applied and is practically unsinkable. As the drawings plainly show the device further 25 description is unnecessary.

I claim:—

1. A device of the class described, of a garment comprising a series of waist buoyant chambers having inflation tubes arranged 40 side by side and independent of each other for inflating the chambers from within and exteriorly of the garment, and a register plate or valve provided with a handle and spring pressed means on top of the plate to 45 prevent the ingress of water.

2. A device of the class described comprising a body portion a head portion having straps and strap holding means and adapted to be tied or drawn above the head 50 of the wearer, a compressible or yieldable bundle adapted to be tied within said head portion for rendering the same water tight, and an elastic cap adapted to be placed over 55 and partly inclose said head portion.

In testimony whereof I have hereunto affixed my signature in the presence of two witnesses.

EMMETT F. X. HICKMAN.
